F. MANKEY.

OPEN WORK PANEL.

No. 16,426.

Patented Dec. 29, 1885.

UNITED STATES PATENT OFFICE.

FREDERICK MANKEY, OF WILLIAMSPORT, PENNSYLVANIA.

DESIGN FOR AN OPEN-WORK PANEL.

SPECIFICATION forming part of Design No. 16,426, dated December 29, 1885.

Application filed November 13, 1885. Serial No. 182,762. Term of patent 7 years.

To all whom it may concern:

Be it known that I, FREDERICK MANKEY, of Williamsport, Lycoming county, Pennsylvania, have invented and produced a new and original Design for Open-Work Panels, of which the following is a specification, reference being had to the accompanying photograph, forming part hereof.

The openings through the panel are octagonal in form, showing four inwardly-convex sides, A B C D, alternating with four straight sides, E F G H. These openings appear in lateral rows, as M N, at regular intervals. The openings of row M alternate with the openings of row N. Upon the face of the panel are diagonally-disposed grooves or channels I J K L. The channels I J extend from the ends of the curved side D in the opening marked 1, for example, to the ends of the

curved side B of the opening marked 2. The channels K L, oppositely inclined, extend from the ends of the curved side C of the opening marked 1 to the ends of the curved side A of the opening marked 3. The channels are repeated between the several openings. 25

I claim—

The design for an open-work panel, substantially as herein shown and described, which consists of the octagonal openings A B C D E F G H, appearing in rows and alternating in adjacent rows, and on the face of the panel the inclined channels I J and oppositely-inclined channels K L. 30

FREDERICK MANKEY.
